UNITED STATES PATENT OFFICE.

PETER STOLBERG, OF SAN FRANCISCO, CALIFORNIA.

BALANCING DEVICE FOR FLYING-MACHINES.

Specification of Letters Patent. Patented Aug. 12, 1913.

1,070,200.

Application filed November 20, 1912. Serial No. 732,520.

To all whom it may concern:

Be it known that I, PETER STOLBERG, a citizen of the United States, residing at San Francisco, in the county of San Francisco and State of California, have invented certain new and useful Improvements in Balancing Devices for Flying-Machines, of which the following is a specification, reference being had to the accompanying drawings.

This invention relates to an improved balancing or stabilizing device for flying machines and has for its primary object to provide a device of this character which is particularly designed for application to a biplane whereby the machine may be readily controlled by the aviator and maintained in a proper position in treacherous air currents.

Another and more specific object of the invention resides in the provision of a pair of spaced wings or planes and means for locking the same in a normal stationary position, said wings being so mounted, that when released, they will move in unison, so as to deflect said currents and maintain the machine upon a proper balance.

A still further object of the invention is to produce a stabilizing device for flying machines which is simple and durable in its construction, efficient and positive in actual use and may be readily applied to biplanes and other machines, as at present constructed without requiring any material alterations therein.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawings, in which—

Figure 1 is a perspective view of a biplane having my improved stabilizing device applied thereto; Fig. 2 is a similar view, showing the position of the stabilizing wings after they have been released; Fig. 3 is a vertical section through one of the wings illustrating the mounting thereof; and Fig. 4 is a transverse section.

Referring in detail to the drawings, 5 and 6 designate the upper and lower planes respectively, of a flying machine of the bi-

plane type. These planes are connected and braced in any preferred manner, and the operator's seat 7 is located centrally upon the lower plane 6.

Adjacent to each end of the lower plane 6, the vertically disposed stabilizing wings or planes 8 are mounted, said wings being of a general semicircular form and normally extending fore and aft between the upper and lower planes of the machine. To the lower edges of the wings 8, the pivot studs 9 are attached said studs being loosely mounted in suitable step bearings 10. Also attached to the lower edge of the wings 8 and adjacent to the opposite ends thereof, are the depending stud bolts 11 which project through arcuate slots 12 in the lower plane 6. A rod 13 is connected at its ends to the spaced wings 8 adjacent to the edge thereof and on the approximate vertical center line of said wings, by means of the ball and socket joints 14. A second rod 15 extends in parallel relation to the rod 13 and is located below and forward of the same and comparatively close to the lower plane 6 of the machine. This latter rod is also connected at its ends by means of the ball and socket joints 16 to the wings 8 adjacent to their forward edges.

The extremities of said rod extend beyond the wings and are provided with crank arms 17 which at their free ends are adapted for engagement in longitudinal slots 18 formed in the lower plane 6. An operating lever 19 is mounted adjacent to the operator's seat 7 and is connected to the lower rod 15 whereby said rod may be shifted transversely to dispose the wings 8 at an inclination with relation to the line of flight of the machine. The lever 19 is fulcrumed intermediate of its ends upon a suitable support, the rod 15 being loosely mounted in the lower end of said lever so that the same may be freely rotated. A suitable handle member 20 is fixed to the rod 15 whereby the same may be turned to throw the ends of the crank arms 17 upwardly out of the slots 18 in the lower plane 6, thus permitting the wings 8 to freely turn from the pivots 9 as a fulcrum to assume various oblique positions longitudinally of the machine. Under normal conditions, however, these wings are locked against such turning movement by the engagement of the crank arms 17 in the slots 18. It will be apparent that as the wings 8 are connected by means of the rods 13 and 15 they will at all times move in unison,

thereby providing an efficient and positively operating balancing means at opposite ends of the machine and preventing the same being overturned when contrary air currents are encountered.

The outward inclination of the wings 8 which is effected by shifting the rod 13 transversely is limited by means of the vertical rods or posts 21 which connect the upper 10 and lower wings 5 and 6. This adjustment of the wings further serves to equilibrate the machine in its flight and also enables the operator to obtain the greatest lifting force from light air currents, the same impinging against the under faces of the wings when they are inclined, thus sustaining the machine in its flight. They may, however, assume an extreme angle of about thirty-five degrees from the perpendicular.

20 From the above description, the construction and operation of the device will be readily understood. When the wings are released by turning the rod 15 to disengage the crank arms 17 from the slots 18, the air 25 currents striking upon the wings 8 will maintain the machine upon a proper balance. The operator may readily adjust said wings to any desired inclination by simply shifting the lower rod 15 longitudinally. 30 The upper rod 13 provides a connecting brace between the wings and prevents the same being broken or distorted by heavy air gusts. The device as a whole is comparatively simple in its construction and it will 35 be obvious that the same can be readily applied to flying machines of the biplane type without necessitating any modification in their construction whatsoever. The stabilizing device is at all times under the instant 40 control of the operator and will effectively prevent overbalancing of the machine when struck by a strong air current upon either side of its center.

While I have shown and described the 45 preferred construction and arrangement of the various parts, it will be understood that the invention is susceptible of considerable modification without departing from the essential features or sacrificing any of the advantages thereof.

50 Having thus described the invention, what is claimed is:

1. The combination with a biplane, of 55 balancing means therefor comprising wings pivotally mounted upon the ends of the lower plane, means to lock said wings

against pivotal movement, said means including a rod connecting the wings, said rod being adapted for transverse shifting movement to dispose the wings at various transverse inclinations with relation to the plane, and means for guiding and limiting the pivotal movement of said wings.

2. The combination with a biplane, of balancing means therefor comprising wings pivotally mounted upon the opposite ends of the lower plane for transverse and longitudinal adjustment, a rod connecting said wings to simultaneously dispose the same at a transverse inclination with relation to the line of flight, a second rod connecting said wings to simultaneously dispose the same at a longitudinal inclination with relation to the line of flight, and locking means carried by said latter rod coöperating with the plane to lock said wings in position against either longitudinal or transverse adjustment.

3. The combination with a biplane, of balancing means therefor comprising wings pivotally mounted upon the opposite ends of the lower plane, said plane being provided with arcuate slots, stud bolts carried by the wings movable in said slots, a rod connecting said wings to simultaneously adjust the same to a longitudinal inclination with relation to the line of flight, and arms fixed to said rod, said plane being provided with slots to receive said arms and lock the wings against adjustment.

4. The combination with a biplane, of 9 wings pivotally mounted upon the opposite ends of the lower plane for transverse and longitudinal movement with relation to the line of flight, a rod connected at its ends to said wings to simultaneously move the same 9 to a transverse inclination with relation to the line of flight, a second rod connecting said wings to shift the same to a longitudinal inclined position with relation to the line of flight, means for guiding and limiting 1 the latter movement of said wings, means for limiting the outward transverse adjustment of the wings, and additional means for locking said wings in their normal position with relation to the plane.

In testimony whereof I hereunto affix my signature in the presence of two witnesses.

PETER STOLBERG.
